INVENTOR.

William Gorman

UNITED STATES PATENT OFFICE.

WILLIAM GORMAN, OF NEW BRITAIN, CONNECTICUT, ASSIGNOR TO RUSSELL & ERWIN MANUFACTURING COMPANY, OF SAME PLACE.

DESIGN FOR A MAIL-BOX FRONT.

Specification forming part of Design No. **7,362**, dated April 7, 1871; application filed July 26, 1873.
[Term of Patent 14 years.]

To all whom it may concern:

Be it known that I, WILLIAM GORMAN, of New Britain, in the county of Hartford and State of Connecticut, have invented a new Design for Mail-Box Front; and I do hereby declare that the following specification, taken in connection with the drawings making a part of the same, is a full, clear, and exact description thereof.

In the drawings, A denotes the plate for a mail-box front, and B is a flap which covers a lozenge-shaped opening in the plate. The plate A and flap B together constitute the mail-box front. The outer edge of the plate is surrounded by raised band a, which intersects with the ornamental figures on the salient points. The central portion of the plate is marked by an elongated lozenge-shaped figure, which incloses an oval shield for the word "Letters," "Mail," "Newspapers," or other suitable word, and the space between the lozenge-shaped central figure and band-line around the edge of the plate is filled in with ornamental scroll figures.

The exterior edge of the plate A may be of any preferred outline, and in place of the ornamental scroll-work shown in the drawing on the face of the plate A any other may be substituted, or ornamentation may be omitted altogether.

The distinctive character of my design is found in the lozenge-shaped central figure B, inclosing a shield for the inscription of "Letters," or other appropriate word, and which indicates the form of the opening in the plate for the reception of mail matter.

What I claim as my invention is—

The design for a mail-box front, composed of a central elongated lozenge-shaped figure, inclosing a shield bearing the word "letters," or other appropriate word for mail matter, substantially as described, and shown in the drawing.

WILLIAM GORMAN.
